UNITED STATES PATENT OFFICE

MIECZYSLAW BARABASZ, OF BALTIMORE, MARYLAND.

ATTACHABLE STITCHLESS BUCKLE.

No. 844,082.

Specification of Letters Patent.

Patented Feb. 12, 1907.

Application filed November 2, 1906. Serial No. 341,674.

To all whom it may concern:

Be it known that I, MIECZYSLAW BARABASZ, a citizen of the United States, residing at Baltimore, in the State of Maryland, have 5 invented certain new and useful Improvements in Attachable Stitchless Buckles, of which the following is a specification.

This invention relates to improvements in detachable one-piece metal buckles.

10 One object of the invention is to construct an improved buckle having three cross-bars which may be formed of a single piece stamped from a sheet of metal and which may be readily attached to the straps or belt 15 which it is to secure together without the necessity of stitching, so as to enable its ready removal from the straps while such straps are being washed or laundered.

Another object of the invention is to improve the construction of a three-bar buckle 20 so as to simplify the threading of the webs or straps and to enable the ready adjustment by the movement of the straps through the buckle and at the same time avoid the liability of the straps slipping after having been 25 adjusted.

Another object of the invention is to provide a buckle which may be utilized for securing surgical bandages to the person by 30 reason of its simplicity in attachment to the straps without stitching, its capability of adjustment without pressure against the body, and also by reason of the fact that it is constructed of a single piece of metal, and therefore 35 capable of being thoroughly cleansed.

I am aware that it has heretofore been proposed to construct buckles having only three cross-bars—such, for example, as is illustrated in the patent to Tuch, No. 470,625, 40 and also in the Woodman patent, No. 89,110; but the construction of those buckles is such that they cannot be stamped out complete from a sheet of metal and are incapable of engaging the web to prevent accidental 45 slipping. By my arrangement of bars and engaging devices the objectionable features of all three-bar buckles now known to me are overcome.

The invention is illustrated in the accompanying drawings, in which—

Figure 1 illustrates a perspective view of the buckle as used for surgical purposes. Fig. 2 shows the same buckle in plan. Fig. 3 shows a perspective view of my improved 55 buckle for ordinary use; Fig. 4, an end view of the same. Fig. 5 shows a sectional view

through the buckle and straps. Fig. 6 illustrates a front face view of the buckle attached to the webs or straps, and Fig. 7 shows a rear view of the buckle and the 60 straps attached.

Referring to the drawings by numerals, 1 designates the two parallel side bars; 2, one end bar; 3, the other end bar, and 4 the central cross-bar. All of these bars are stamped 65 from a plate of sheet-steel in such manner as to form a flange 5, which projects inwardly from the outer edge of at least three of said bars, whereby to stiffen the buckle-plate and enable a thin sheet of steel to be employed 70 with good results.

By reference to Figs. 1, 3, and 5 it will be noted that the central cross-bar 4 has an inclined position with respect to the two end bars—that is, one longitudinal edge 6 of the 75 bar 4 has position in a plane beneath or below the outer surface of the bars 1, 2, and 3—while the other edge 7 of said bar has position in a plane substantially in line with said outer surface and is provided with a plurality 80 of sharp-pointed teeth 8, which project outwardly in an inclined direction. The inclination, however, of this central cross-bar and the pointed teeth thereon may be varied and may be more or less than that shown. Ad- 85 vantageous results are gained by thus inclining this central cross-bar. For example, it enables the web or strap to be readily fed through the slot 9. It insures and compels the teeth 8 to engage the under strap to hold 90 it in the adjusted position, and it removes one sharp edge 6 of the cross-bar from the path of the under strap during its adjust- 95 ment and enables said adjustment to be made with a minimum amount of friction, and con-sequently without wear or strain on the straps. By reference to Fig. 5 it will also be noted that the flange 5 on the end bar 2 performs a useful function in addition to its utility as a stiffening means, in that it serves as a friction edge which presses against the free end of the outer strap 10 and prevents this strap from working or moving backward toward the central bar and by such backward move- 100 ment carrying with it the inner strap 11, 105 which latter might thus work over the teeth 8 and become loose.

In the present instance I prefer to arrange the teeth 8 on the central bar in pairs and to locate said pairs of teeth at opposite ends of the bar. The object and advantage of this construction and arrangement of the teeth is

that in the formation of the straps 10 and 11 when the latter are attached to the rear or back of men's garments the opposite edges 12 of the straps are thicker than the portions 5 between the said edges by reason of the fact that the cloth or material from which the straps are made is turned under and then stitched, as at 13, to prevent the said edges from raveling out. This construction therefore forms a double thickness of material 10 along said longitudinal edges, and if the central cross-bar had but a single tooth at each end said single tooth might fail to properly engage the material and permit the strap to 15 slip from its adjusted position. By providing two teeth at each end of the bar said teeth engage the strap on opposite sides of the stitch-line 13 and the engagement with the strap is insured and the objection explained 20 overcome. The end bar 3 is also provided with sharp-pointed teeth 14, which project therefrom and turn inwardly toward the inner side of the buckle.

It will thus be seen that the peculiar combination 25 of three cross-bars with the outwardly and inwardly pointed teeth all coact in such a manner as to enable the straps to be easily fed through the buckle, permit their ready adjustment when desired, and insure a positive engagement between the outwardly 30 and inwardly projecting pointed teeth and the two straps to prevent slipping of said straps after the adjustment has been made.

It will also be seen that the buckle is made 35 from a single plate and the teeth arranged in such manner as to enable the formation of the entire buckle by a die.

The end bars 1 are both provided with the flange 5; but this flange has a curved edge 15, 40 which serves to broaden the flange at a central point adjacent the central cross-bar, and thereby facilitate the grasping and manipulation of the buckle during the act of threading and adjusting the straps.

In addition to the features hereinbefore described, which are common to the buckles shown in all the figures of the drawings, I provide a slot 16 in the end bar 3, as shown in Figs. 1 and 2, and a tab 17 or piece of webbing of any suitable material is passed through 45 said slot, so as to enable the buckle to be drawn along the outer strap 10 to shorten the latter when employed for surgical purposes. It is obvious that by grasping the free end of the outer strap and holding it under tension the buckle may be readily drawn by the tab or webbing 17 without pressure on the buckle-plate.

Having thus described my invention, what 50 I claim as new, and desire to secure by Letters Patent, is—

1. A buckle comprising a single plate having two side bars; two end bars which con-

nect the side bars and one of said end bars having teeth at its inner edge, and an inclined toothed bar between the end bars, the teeth of the inclined bar confronting the teeth of the end bar. 65

2. A buckle comprising a single plate having two side bars, two end bars connecting 70 the side bars and one of said end bars having a plurality of teeth which project from the inner side and beyond the inner surface of the buckle-plate and said buckle also having an inclined cross-bar with teeth along its 75 outer edge.

3. A buckle comprising a single plate having side bars, end bars connecting the side bars and one of said end bars having a plurality of teeth along its inner edge and said 80 buckle also having a central bar with a pair of teeth at each end thereof—said pairs of teeth on the central bar projecting toward the end bar with the teeth.

4. A buckle comprising a single plate having side bars, end bars connecting the side bars and one of the end bars having teeth which are pointed and are bent inwardly beyond the inner surface of the buckle-plate 85 and said buckle having a cross-bar between 90 the end bars—said cross-bar also having pointed teeth which project outwardly and beyond the outer surface of the buckle-plate.

5. A buckle comprising a single plate having side bars, end bars connecting the side bars and one of the end bars having a plurality of inwardly-bent teeth, while the other end bar is toothless—said side bars and toothless end bar having a flange at their outer edges, and a central cross-bar having 100 teeth which project outwardly beyond the buckle-plate and which confront the teeth on the end bar.

6. A buckle comprising a single plate having side bars, a toothless flanged end bar connecting one end of the side bars; a flangeless toothed bar connecting the other end of the side bars and provided with a slot and a cross-bar also connecting the side bars between the two end bars and said cross-bar 110 having teeth at that side which confronts the teeth of the end bar.

7. A buckle comprising a single plate having side bars, end bars connecting the side bars and one of said end bars having teeth; 115 means attached to the toothed end bar by which the latter may be drawn laterally, and a cross-bar also connecting the side bars and having teeth which project laterally toward the end bar with the teeth.

In testimony whereof I affix my signature in presence of two witnesses.

MIECZYSLAW BARABASZ.
